COMBINED THREAD CUTTER AND HOLDER

Application filed May 17, 1930. Serial No. 453,376.

This invention relates to improvements in thread holders for weft ends of automatic looms and it is the general object of the invention to provide an easily operated motion 5 of this type having a cutter which can be actuated by the same means which controls the thread holder.

In a form of thread holder which has gone into use in multicolor weft replenishing 10 looms there are several weights having normally closed coil tension springs, the coils of the springs gripping the several weft ends between them. The weights are movable downwardly in guides to take up any slack 15 which occurs in the weft ends and a cutter is provided for severing excess lengths of ends. It is an important object of my present invention to provide a manually operated device 20 by means of which the weighted thread holder and the cutter may be operated by a single motion on the part of the weaver.

It is a further object of my present invention to provide means whereby the cutter may be opened and the coils of the spring expanded to receive weft ends by a single means 25 which may be actuated by the operator.

It is another object of my present invention to provide means for raising and expanding the springs and then subsequently 30 operating the cutter while the springs remain raised, these results being achieved by a single and easily operated contrivance. In the operation of the device set forth hereinafter a manually operated device is effective to expand the closed coils, the latter receiving the 35 weft ends between them, and exerting a tensile strain which tends to lower the manually operated device to a position where the latter will be out of position to interfere with 40 downward slack taking-up movements of the weft ends.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a front elevation of a portion of a

weft replenishing magazine having my invention applied thereto,

Fig. 2 is a side elevation on an enlarged scale taken in the direction of arrow 2, Fig. 1,

Fig. 3 is a vertical section on line 3—3 of Fig. 2,

Fig. 4 is a top plan view taken in the direction of arrow 4, Fig. 3,

Fig. 5 is a vertical section through one of the weighted thread holding elements,

Fig. 6 is a detail vertical section on line 6—6, Fig. 2, and

Fig. 7 is a detail horizontal section on line 7—7 of Fig. 3.

Referring to Fig. 1 I have shown a weft replenishing mechanism 10 having arranged therein a stack of reserve bobbins 11 from each of which extend a weft end 12. It is to be understood that there will be several stacks of reserve bobbins and that the weft ends will be arranged in groups, one for each stack. One of the tie rods 13 which form a part of the construction of the replenishing mechanism is extended and supports a frame 14 having a series of vertical holes 15 therein. Slots 16 extend to the left from the holes as seen in Figs. 3 and 4.

In each of the holes 15 is a thread holder designated generally at 17 and having a weighted element 18 provided with a vertical bore 19 through which extends a rod 20. The upper end of the rod is secured to a head 21 while the lower end is provided with a lifting foot 22. The member 18 and head 21 are provided with shoulders 23 which grip the end coils of a tension spring 24. Each spring has normally closed coils formed of a wire the lower end of which is extended to form a finger 25 movable through one of the slots 16.

A plate 26 is secured to the top part of the frame 14 and has secured thereto a lower cutter blade 27 to cooperate with a movable blade 28 movably pivoted around a tie rod 18. A collar 29 adjustably mounted on the tie rod varies the pressure which is exerted by compression spring 30 on pad 31 bearing against the cutter 28.

At the beginning of the weaving operation the weights will be raised until the fingers 25 engage the bottom of plate 26, after which

continued upward movement of the rods 20 will expand the springs so that the weft ends 12 may be passed between the separated coils, subsequent contraction of the coils gripping the weft ends. The cutter 28 may 5 then be depressed to sever excess length of weft ends and as successive transfers take place in the replenishing mechanism the weights will descend to keep the weft ends substantially taut.

10 The matter thus far described forms no part of my present invention.

In carrying my invention into effect I provide improved means for raising the 15 weighted elements and expanding springs 24, and also operating the cutter 28. Accordingly, I provide the frame 14 with a bearing 40 through which extends a rod 41 to the lower end of which is secured a lifter plate 20 42. The latter is positioned to lie under all of the feet 22 and is adjustable on the rod 41 by means of screw 43. The upper end of the rod 41 passes through a guide 44 secured to the movable cutter 28 and having a slot 45 25 to permit angular movement of the blade while the rod 41 moves along its axis. A hand hold 46 is secured to the top of the rod 41 and there is located between the bearing 40 and the guide 44 an adjustable collar 47 30 to engage the guide 44 for the purpose of raising the cutter blade. A stop 48 fixed to the frame 14 limits downward movement of the blade 28 and also the parts moving with the rod 41.

35 In order to keep the lifter plate 42 correctly aligned with the feet 22 I slab the rod 41 as at 49 and thread a screw 50 into the bearing 40 to have guiding relation with the rod and prevent angular movement thereto. 40 Screw 50 is spaced slightly from the flattened part of the rod so as to permit free vertical motion of the latter.

When it is desired to raise the weighted members 18 as previously described the operator will grasp the hand hold 46 and elevate the same to cause plate 42 to raise all the 45 feet 22. After the fingers 25 engage the bottom of the plate 26 the operator will continue to raise the hand hold, thereby expanding all of the springs. During the latter part 50 of the upward movement of the rod 41 the collar 47 will engage the guide 44 to lift the cutter blade 28 to the dotted line position shown in Fig. 2, thereby providing a notch 55 or space into which the operator may lead weft ends extending from the newly inserted reserve bobbins.

After the weft ends have been secured to the springs the operator will depress the rod 60 41 until it assumes the position shown in Fig. 2, this operation accomplishing two results, namely, closing the cutter blades to sever the excess length of weft ends, and lowering of the plate 42 so as to permit the weighted members 18 to move downwardly to the full

extent of their motion. Downward motion of the cutter blade 28 from its highest position is assisted by the expanded springs, which are under tension when the blade is raised.

70 It will be seen by reference to Fig. 2 that the notch into which the weft ends are led is defined partly by the bottom of the cutter blade 28 which is inclined downwardly and toward its pivot. The upper ends of the 75 heads 21 will be in a substantially horizontal line, so that the springs which are farthest from the pivot of the cutter blade 28 will not interfere with movement of weft ends to the springs which are nearer said pivot. The 80 lifting collar 47 may be placed at any point along the length of the rod 21 which will give most advantageous lifting of the blade 28.

85 From the foregoing it will be seen that I have provided a simple means for raising the gravity actuating thread holder and at the same time opening the cutter. It will also be noted that by reverse movement of the rod 41 the cutter blade 28 may be positively closed to sever excess length of weft ends and that 90 the plate 42 will thereby be lowered to a position where it will not interfere with the downward movement of the weighted members 18. Furthermore, when the blade is in raised position it is diagonally disposed with respect to a horizontal line and therefore affords access to all of the expanded springs despite the fact that the heads 21 may be raised. 95 It will also be seen that when the plate 42 is raised sufficiently to open the coils of the 100 springs the latter exert a downward force which tends to lower said plate so that the same will move to a position where it will not interfere with downward slack taking-up movement of the springs and associated parts. 105

Having thus described my invention it will be seen that changes and modifications may be made therein by those skilled in the art without departing from the spirit and scope 110 of the invention and I do not wish to be limited to the details herein disclosed, but what I claim is:

1. In a loom having reserve bobbins from which extend weft ends, a movable thread holder, a cutter to sever excess length of weft 115 ends extending from the holder, and a single means to open and close said cutter and also move the thread holder to thread receiving position.

2. In a loom having reserve bobbins from which extend weft ends, a movable thread holder, a cutter to sever excess length of weft ends extending from the holder, and means to simultaneously raise the thread holder to thread receiving position and open the cutter. 120

3. In a loom having reserve bobbins from which extend weft ends, a movable thread holder, a cutter to sever excess length of weft ends extending from the holder, a single device movable with respect to the holder to 125

- move the latter to thread receiving position and also to open the cutter.
4. In a loom having reserve bobbins from which extend weft ends, a movable thread holder, a cutter to sever excess length of weft ends extending from the holder, an operating device having lifting means for raising the thread holder to thread receiving position and having other means for giving the cutter a cutting stroke, the operating device moving the lifting means out of the path of the thread holder when giving the cutter its cutting movement.
5. In a loom having reserve bobbins from which extend weft ends, a movable thread holder, a cutter to sever excess length of weft ends extending from the holder, and means to simultaneously move the thread holder and cutter to thread receiving position.
6. In a weft replenishing loom having reserve bobbins from which extend weft ends, a frame, a thread holder to be secured to the weft ends and movable downwardly in said frame to hold the weft ends taut, and a cutter pivotally mounted with respect to the frame to sever excess length of weft ends extending beyond the thread holder, a device supported by and movable with respect to the frame and effective to simultaneously raise the thread holder to thread receiving position and to open the cutter.
7. In a weft replenishing loom having reserve bobbins from which extend weft ends, a frame, a thread holder to be secured to the weft ends and movable downwardly in said frame to hold the weft ends taut, and a cutter pivotally mounted with respect to the frame to sever excess length of weft ends extending beyond the thread holder, an operating device supported by and movable vertically with respect to the frame, a lifting element secured to the device to raise the thread holder to thread receiving position, a cutter engaging element secured to the device to open the cutter when the thread holder is raised, and means to depress the device to close the cutter and move the lifting member out of the path of the downward movement of the thread holder.
8. In a weft replenishing loom having reserve bobbins from which extend weft ends, a weighted normally closed coil spring thread holder movable downwardly under the action of gravity, movable means to be operatively related to the thread holder to lift the same and expand the spring to open the coils to receive weft ends, said spring when expanded tending to exert a force on said means to move the same downwardly out of engaging position with respect to the thread holder.
9. In a weft replenishing loom having reserve bobbins from which extend weft ends, a normally closed coil tension spring to have operative connection with the weft ends, said spring being movable downwardly to take

up slack in the weft ends, means to be raised to lift the spring against the action of gravity and also to expand the coils thereof to place the spring under tensional strain to receive the weft ends, said strain tending to lower the lifting means to a position where the latter will be out of engaging position with respect to the spring as the latter moves downwardly.

10. In a weft replenishing mechanism having reserve bobbins from which extend groups of weft ends, a plurality of vertically movable thread holders each to have operative engagement with a group of weft ends, a cutter blade to remove excess length of weft extending beyond the thread holders, means to raise the thread holders and simultaneously open the cutter, the cutter having an edge oblique with respect to the plane of the upper portions of the thread holders to define an angular notch through which the weft ends may be passed.

11. In a weft replenishing loom having reserve bobbins from which extend weft ends, a thread holder element to be moved to thread receiving position, and a thread cutter element to be moved to thread receiving position and subsequently to thread cutting position, and a single means effective to give said elements their respective movements.

12. In a weft replenishing loom having reserve bobbins from which extend weft ends, a fixed structure, a thread holder for the weft ends movable in the structure, a thread cutter for the weft ends, a pivot on the structure for the cutter, and a device between the pivot and holder to actuate the cutter.

13. In a weft replenishing loom having reserve bobbins from which extend weft ends, a fixed structure, a thread holder for the weft ends movable in the structure, a thread cutter for the weft ends, a pivot on the structure for the cutter, and a device between the pivot and holder to move both the cutter and thread holder.

14. In a weft replenishing loom having reserve bobbins from which extend weft ends, a thread holder comprising a closely wound coil spring connected to the weft ends and tending to move in a given direction to take up slack in the weft ends, and a device to be operatively related to the spring and movable in a direction opposite to said given direction to expand the coils of the spring, said spring when expanded exerting a force tending to move said device in said given direction toward a position where said device will be out of engaging position with the holder.

In testimony whereof I have hereunto affixed my signature.

HAROLD L. BLANCHARD.
